FLUID FILTER

Charles M. Tursky, Neshanic, N. J.

Application November 13, 1951, Serial No. 256,059

7 Claims. (Cl. 210—165)

1

This invention relates to filters for use in filtering fluids of various types and kinds. More particularly, the invention deals with a device of this kind employing a filter unit, or assemblage, which is readily detachable with respect to the casing of the device and, particularly, wherein floating or freely movable tubes are disposed within the filter coils, so as to encourage vibratory or other movement of the tubes facilitating filtering operation.

Still more particularly, the invention deals with a device of the character described, having valve control means at the lower portion thereof for draining condensation and foreign particles from respective chambers of the device.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a longitudinal sectional view through a filter device made according to my invention, diagrammatically illustrating the filter coils and tube mountings.

Fig. 2 is an enlarged broken section of one of the tubes and part of a coil arranged thereon, clearly illustrating clearances provided for circulation of filtered fluid through the device.

Fig. 3 is an enlarged plan view of the structure, as seen in Fig. 1, with parts of the construction broken away.

Fig. 4 is a section on the line 4—4 of Fig. 1, with part of the construction broken away.

In Fig. 1 of the drawing, I have shown, at 10, the tubular casing, or cylinder, of the filter device or apparatus, the casing having a downwardly inclined bottom wall 11, having a large opening 12 therein. The upper portion of the casing has an outwardly extending flange 13, upon which a coupling ring 14 is adapted to bear, the ring being generally of the peripheral contour of a closure plate or head 15, note Fig. 3, and a plurality of bolts 16 are employed at corner portions of the head 15 and ring 14 for clamping the head onto the casing 10, the flange 13 seating upon a ring gasket 17 in the head, as clearly seen in Fig. 1 of the drawing.

Centrally of the head 15 is a tubular portion 18 which extends into the casing 10 and mounted thereon is a coil or gas resistant rubber ring 19 which is self-sealing against the pressures which may prevail.

At one side of the head 15 is an admission port 55 42'. The plate 45, 45' of each head has a plu-

2

20, into which the fluid, such as oil, gas or the like is adapted to pass from a source of supply, not shown, under a predetermined pressure. At 21 is shown a vertical port for placing the port 20 in communication with the chamber 22 of the casing.

At the opposed side of the head 15 is an exhaust port 23, which communicates with the bore 24 of the tubular portion 18 for discharge of filtered fluid to a suitable receiving station, not shown, in the manner more specifically described hereafter.

At the lower portion of the casing 10 and fitting in the aperture 12 is a tubular bearing member or sleeve 25. This member has a reduced upward extension 26, on which is mounted a sealing ring 27, similar to the ring 19. The bore 28 of the member 25 is threaded to receive a valve body 29 which seats on a sealing ring or gasket 30 on the bottom wall 11 of the casing. This construction secures and positions the member 25 centrally of the bottom of the casing, as will be apparent.

Mounted transversely of the valve body 29 is a tapered valve 31, having diverging ports 32 for placing the discharge 33 of the body 29 in communication with ports 34 opening into an annular chamber 35 in said body.

The member 25, adjacent the bottom wall 11 of the casing, has circumferentially spaced recesses 36, which place the lower drain or sediment chamber 37 of the casing in communication with the annular chamber 35.

The valve 31 has a port 38 which is adapted to register with a bore 39 in the body 29 opening into the bore 28 to drain a chamber 40 formed in the lower portion of a filter unit 41.

The filter 41 comprises two heads 42, 42' which are of similar or identical construction, the head 42 being disposed at the lower portion of the filter in the construction shown, but this head might assume the upper position of Fig. 1. Each head comprises a casing part 43, 43' having a hub portion 44, 44' to engage the sealing rings 27, 19, respectively, and a plate portion 45, 45'. The plate portion 45 and the casing part 43 forms the chamber 40, whereas 43', 45' form a corresponding chamber 40', with which the bore 24 communicates for the discharge of filtered fluid through the port 23.

In view of the reduced dimensions of the showing in Fig. 1, Fig. 2 has been illustrated to show, on an enlarged scale, the mounting of the filter coils and tubes in connection with the heads 42, 42'.

The plate 45, 45' of each head has a plu-

rality of radially and circumferentially spaced ports, or passages, 46, 46', in enlarged portions of which are mounted flanged cups or bushings 47, 47' forming seats for end portions of spring-like filter coils 48, or filter elements of any type or kind which are of tubular construction. Characteristics of the filter coils will depend largely upon the type of fluid being filtered and, while coils of the type and kind shown in Fig. 6 of my prior Patent Number 2,458,118 of January 4, 1949, may be employed, I have indicated in Fig. 2, at 48, coils having circumferentially spaced projections, as at 49, controlling the filter passages between the coil's in accordance with the teachings in my application, Serial Number 183,553; filed September 7, 1950.

Disposed within each of the filter coils 48 is a tube 50, preferably of a non-corrosive material, and this tube is of less outside diameter than the interior of the coil 48 and also of the passages 46, 46', as will clearly appear from a consideration of Fig. 2. In this case, it is to be kept in mind that the clearances herein referred to are not attempted to be shown in Fig. 1 and, for this reason, Fig. 2 has been provided to clearly show the passages 46, 46', as well as the chamber 51 between each tube 50 and the coil 48. It will, thus, be seen that fluid introduced into the chamber 22, note Fig. 1, must first pass through the coils 48, thus into the chamber 51 and then into the chambers 49, 49' at the heads 42, 42' and this filtered fluid is free to pass through the tubes 50 into the chamber 49' for discharge through the ports 24, 23.

In this connection, it will be noted that the walls of the casings 43, 43' are tapered or sloping so that clearance is provided between the lower ends of the tubes 50 and the tapered walls of the casing 43. The same result would be accomplished if the unit 41 were mounted in the filter in the reverse direction.

It will appear from a consideration of Fig. 1 of the drawing that the parts 43, 45; 43', 45' are secured together by screws or other fastenings, as at 52, 52' and a center bolt and spacing member 53 is employed for coupling the heads 42, 42' in predetermined spaced relationship to each other, thus keeping the unit assemblage between the heads 42, 42'.

It will be understood that the tubes 50 have a free vertical as well as lateral movement within the coils 48, thus these tubes are subjected to sideways vibratory movement in pressure injection of fluid to be filtered through the coils onto the tubes and are also free to move vertically in the unit, as will be apparent.

In Fig. 1 of the drawing, the valve 31 is shown in its opened position in order to clearly illustrate the port arrangement. However, by operating the fingerpiece or handle 31' of the valve, the same can be moved into closed position to seal the discharge 33 when the filter device, or apparatus, is in operation. It will also be apparent that the upper end of the port or bore 24 is sealed by a plug 54.

In the use of the filter, it will be understood that gasoline, oil or other fluid can be introduced into the chamber 22 through the ports 20, 21 and pass through the multiplicity of filters 48 employed and, then, into the chambers 51 and through the ports 46, 46' and tubes 50 finally into the chamber 49' and, then, out through the ports 23, 24. In this operation sediment is adapted to be collected in the chamber 37, as well as water or the like and water may also be

collected in the chamber 40 or the chamber 28 and passage 39, so that, from time to time, and, particularly, when the filter operation is at rest, foreign particles, water and the like may be discharged through the discharge 33 by moving the valve 31 into open position.

My improved device, or apparatus, lends itself for cleaning or repair by quick detachment of the head 15 which facilitates removal of the unit 41 from the casing 10. It will also be understood that, in some instances, it will be possible to provide a reverse circulation of fluid through the device or apparatus by admission of fluid through the port 23 and discharge of sediment or the like, including fluid through the port 20, although, in some instances, such, for example, as the filtration of gasoline, this is not necessary by virtue of the drainage provided for water or condensation and foreign particles, here keeping in mind that vibratory movement of the tubes, including the filter elements will encourage deposit of the solids or foreign particles in the chamber 37 for intermittent discharge by movement of the valve 31 into open position.

The rings 17, 19 and 27 can be composed of any suitable material resisting the fluids circulated through the filter and, when gasoline is being filtered, neoprene material can be employed. In this connection, the bushings 47, 47' can also be made of such material so as to effect a seal of the filter elements 48 in the plates 45, 45'.

Having fully described my invention, what I claim as new and desire to secure by Letters Patent is:

1. A filter of the class described, comprising a casing having a valve controlled drain at the lower end thereof, a plate detachable with respect to the upper, open end of the casing, said plate having intake and discharge passages, a filter unit detachable with respect to the casing through the open end thereof, said drain and said plate having alined bearings for detachable mounting and alinement of the unit in the casing, said unit comprising identical chambered heads, said heads being formed by flat inner and sloping outer plates secured together to form the chamber therebetween, means coupled with the inner plates for joining and spacing said plates, the inner plates having alined apertures spaced circumferentially and radially thereon, filter coils seating in and extending between said alined apertures, said apertures opening into the chambers of said heads, open tubes freely mounted in and movable longitudinally of the filter coils and the apertures of said heads, the intake passage of said plate communicating with the casing, and the discharge passage of said plate communicating with the chamber of said head mounted thereon for discharge of filtered fluid from the device.

2. A filter of the class described, comprising a casing having a valve controlled drain at the lower end thereof, a plate detachable with respect to the upper, open end of the casing, said plate having intake and discharge passages, a filter unit detachable with respect to the casing through the open end thereof, said drain and said plate having alined bearings for detachable mounting and alinement of the unit in the casing, said unit comprising identical chambered heads, said heads being formed by flat inner and sloping outer plates secured together to form the chamber therebetween, means coupled with the inner plates for joining and spacing said plates, the inner plates having alined apertures spaced circumferentially and radially thereon, filter coils

seating in and extending between said alined apertures, said apertures opening into the chambers of said heads, open tubes freely mounted in and movable longitudinally of the filter coils and the apertures of said heads, the intake passage of said plate communicating with the casing, the discharge passage of said plate communicating with the chamber of said head mounted thereon for discharge of filtered fluid from the device, and said valve control drain communicating with the lower portion of said casing and with the chamber of the lower head.

3. In filter devices of the character described, a filter unit including a plurality of elongated filter coils, comprising two identical heads, each head having an outer plate with an outwardly projecting central tubular bearing and an inner plate having circumferentially and radially spaced apertures, means coupling said plates together, the outer plate having an outwardly sloping wall spaced from the inner plate to form, in the head, a chamber, means directly coupled with the inner plates for coupling and spacing said plates and the heads, bushings seated in enlarged portions of the apertures of said inner plates, said bushings forming bearings for opposed ends of the elongated filter coils extending between said inner plates, and open tubes freely mounted for longitudinal movement in the apertures of said inner plates and said coils and extending into the chambers of said heads and movable toward and from the outer plates of said heads.

4. In filter devices of the character described, a filter unit, comprising two similar heads, each head having an outer plate with an outwardly projecting central tubular bearing and an inner plate having circumferentially and radially spaced apertures, means coupling said plates together, the outer plate having an outwardly bevelled wall spaced from the inner plate to form, in the head, a chamber, means directly coupled with the inner plates for coupling and spacing said plates and the heads, filter coils mounted in the apertures of said inner plates and extending between said plates, means for sealing the mounting of the coils in said plates, and elongated tubes freely mounted in the apertures of said inner plates and said coils and extending into the chamber of said heads to form passages between the coils and tubes opening into the chambers of said heads.

5. In filter devices of the character described, a filter unit, comprising two similar heads, each head having an outer plate with an outwardly projecting central tubular bearing and an inner plate having circumferentially and radially spaced apertures, means coupling said plates together, the outer plate having an outwardly bevelled wall spaced from the inner plate to form, in the head, a chamber, means directly coupled with the inner plates for coupling and spacing said plates and the heads, filter coils mounted in the apertures of said inner plates and extending between said plates, means for sealing the mounting of the coils in said plates, elongated tubes freely mounted in the apertures of said inner plates and said coils and extending into the chamber of said heads to form passages between the coils and tubes opening into the chambers of said heads, said tubes being movable toward and from the outer plates of said heads, and the outer plates of said heads having means for mounting the device in connection with a suitable support.

6. A filter device comprising an elongated casing having a closed apertured end and an open outwardly flanged end, a plate for closing the open end, a ring engaging the flange for securing the plate to the casing, means sealing the casing on said plate, said plate having a tubular bearing portion extending centrally into the casing, a tubular valve body mounted in the aperture of the closed end of said casing, a sleeve engaging the valve body in clamping the same on the closed end of the casing, said sleeve having an inwardly projecting bearing portion in axial alinement with the bearing portion of said plate, a filter unit arranged in the casing and supported on said bearing portions, means on the bearing portions engaging the unit to effect a seal thereon, said filter unit comprising a pair of identical chambered heads having sloping walls, the heads including plates having alined apertures, means 10 engaging said head plates for coupling and spacing said heads, a plurality of filter coils arranged in said alined apertures bridging said heads and communicating with the chambers thereof, a plurality of open end tubes freely disposed in 15 said coils and alined apertures and opening into the chambers of said heads, said tubes being movable longitudinally of the coils and in said apertures, means for introducing a fluid to be filtered through said plate and into the casing around 20 said filter unit, and said plate having an exhaust passage communicating with the chamber of the head mounted on the bearing of said plate for discharging filtered fluid from the device.

7. A filter device, comprising an elongated 35 casing, open at the top and having a valve controlled drain at the lower end thereof, a plate having intake and discharge apertures, said plate closing the upper open end of the casing, a filter unit having identical chambered heads having sloping walls, the heads including plates having alined apertures, means engaging said head plates joining and spacing said heads, said heads having outwardly projecting means engaging said plate and drain for alining the unit in the casing, a plurality of open end tubes freely movable in 40 said alined apertures and bridging the heads and opening into the chambers of said heads, filter coils spaced from and enveloping the tubes and sealed in said heads, the spacing of said coils from the tubes forming annular passages opening into the chambers of said heads, said intake passage of the plate communicating with the casing for admitting fluid to be filtered, the discharge passage of said plate communicating with the chamber of the head mounted thereon for 45 discharging filtered fluid from the device, and means for sealing the heads on said plate and drain.

CHARLES M. TURSKY.
